DEAERATOR AND DIRT SEPARATOR

Filed March 19, 1945

UNITED STATES PATENT OFFICE

2,571,503

DEAERATOR AND DIRT SEPARATOR

Arthur F. Underwood, Grosse Pointe, Mich., assignor to General Motors Corporation, Detroit, Mich., a corporation of Delaware

Application March 19, 1945, Serial No. 583,611

2 Claims. (Cl. 183—2.5)

1

The separation of contained gas and of solid particles from a flowing liquid column is the subject of this invention.

It is an object of the invention to cause the column of liquid moving under the influence of a pump to traverse a path of special form such that foreign matter is readily separated. Other objects such as efficiency, simplicity and economy should be included.

The invention is illustrated by the accompanying drawing wherein:

Fig. 1 is a view in longitudinal section of the apparatus.

Fig. 2 is a section on line 2—2 of Fig. 1.

Fig. 3 is a longitudinal view of a modified form.

Fig. 4 is a view in section, the plane of the section being marked on Fig. 3.

Fig. 5 is a view corresponding to Fig. 3 but showing a second modification.

Fig. 1 and Fig. 2 illustrate a first form. A casing is designated by numeral 7. To it is secured a cover 9. The casing is generally cylindrical but one end, its lower end as shown, is conical as at 11 and terminates in a tubular extremity 13. The cover is similarly conical and has a tubular terminal end 15 which provides an inlet conduit of uniform internal cross section as shown in Figure 1. Within the casing and cover is an inner plug 17 which may be hollow or solid and is shaped as shown to conform to the casing and cover. The plug is formed with spiral vanes 19. The annular space between the plug and the casing is small. The total cross-sectional area may be substantially equal to the cross-sectional area of the tubular part of the cover at 15. The number of vanes need not be large, only enough to give a rotational motion to the fluid passing through the annular space. The space between the upper conical portion of the plug 17 and the upper conical portion 9 of the casing 7 provides a connecting portion between the inlet 15 and the spiral passage portion formed by the guides 19 between the cylindrical portion of the plug 17 and the casing 7. The space between the lower conical portion of the plug 17 and the lower conical portion 11 of the casing 7 provides a connecting portion between the spiral passage portion and the outlet or tubular extremity 13 which is connected to the separation tube 21. As pointed out above the conical passage between the outer portion of the casing 7 or the spiral passage portion and the separation tube allows a substantial or approximately one-third reduction in diameter to increase the speed of rotation of the fluid. It is

2

suggested that the angle of the vanes be from 45° to 60° to the axis.

To the tubular extension 13 is threaded a tubular member 21 of uniform diameter. The end of the tubular member 21 remote from the casing is in threaded engagement with a tubular outlet 23. Thus the tubular member 21 and the tubular outlet member 23 may be best described as a separation tube. At the junction of tubes 21 and 23 located adjacent the lower end of the separation tube the former may be given an internal flare so that a shoulder 25 is formed. Adjacent this shoulder is an outlet pipe 27. Tube 23 is formed with a lug or enlargement 29 having a bore 31 extended to the axis of the tube. A second outlet pipe 33 communicates with this bore 31.

It will be understood that the tubular part 15 is the inlet for liquid and the axial passage from part 23 is in the outlet. If the apparatus is used for cleaning oil containing air and dirt, a pipe from any suitable oil pump may be connected at 15 and suitable conduit means leading to bearings, for example, may be connected at 23.

After entering at 15 the oil under pressure from the pump is forced through the annular passage and is given a rotational motion by the vanes. Upon reaching the separation tube, which is of much smaller diameter, the angular speed is greatly increased. Because of this great angular speed the relatively heavy particles are thrown to the outside of the tube where they wash down to the collector ring 25 and escape through pipe 27. Since the liquid is spinning freely, no secondary flows occur as in the apparatus of some prior devices. Thus there is less tendency for the foreign matter to remain in suspension. Any contained gas in the liquid, tending, of course, to be in the axis of the rotating column, escapes through passage 31. The oil, in this way freed from foreign matter, flows off through tube 23.

The efficiency depends upon the relative dimensions of the casing 7 and tube 21. The difference should be as great as possible giving consideration to the consequent pressure drop. Applying this theory to a practical structure as illustrated in the drawing an elongated separation tube having a diameter substantially less than the diameter of said casing is employed.

In Figs. 3 and 4 there is shown a casing 41 having a cover 43. The separation tube 45 of this form is connected to the casing at 47. A modified air and oil outlet member is marked 49. It is connected to the separation tube at 51 where any convenient form of dirt collector ring 53 is located from which ring the escape pipe 55 carries

the heavy particles of dirt. The oil outlet ring 49 has an axial air escape passage 57 connected to an air pipe 59. The oil leaves at the opening marked 61. The oil enters the separator through the opening 63 which has a uniform diameter through its length and the terminal or connecting portion at the inside of the casing 41 as illustrated in Figure 3. The rotational flow of oil in this form is effected by a tangential opening 63 extending through the side wall of the casing 41. The oil, given the rotational movement in casing 41, has its velocity increased in the smaller separation tube 45 and the foreign matter escapes as before by way of pipes 55 and 59.

Fig. 5 represents a form corresponding to that of Fig. 3 but differing in having a cover of different form. The cover 71 is threaded to casing 73. It has a centrally depressed region at 75 intended to cooperate with the tangential inlet passage 63 in effecting the circumferential flow of the fluid in the casing before it enters the separation tube 45. In other respects the form shown by Fig. 5 is like that of Fig. 3.

I claim:

1. A vortex separator for separating foreign matter from a flowing viscous liquid stream, said apparatus comprising an inlet conduit of uniform internal cross-sectional area, a casing having a smooth cylindrical internal side wall and end walls, connecting means between said conduit and said cylindrical casing having an internal area at least as large as said conduit to maintain constant velocity flow and thereby minimize friction losses, said inlet conduit and casing being so arranged to cause the fluid to rotate about the axis of said cylindrical casing, an elongated separation tube having a diameter substantially less than the diameter of said casing and having one end connected to said end wall of the casing concentric with said axis, said separation tube having a threaded joint adjacent the other end between an upper and lower portion, the upper portion of said separator tube being internally relieved at said joint to provide a dirt recess, the upper edge of the lower portion of said separator tube having an outwardly tapered end to provide an outwardly sloped dirt collecting surface at the base of the recess, a laterally directed outlet pipe to drain dirt from the recess, a relatively small air outlet pipe in the center of said lower portion of said separator tube having the inlet centrally located just below the threaded joint said separator tube discharging the liquid free of dirt and air below said air outlet pipe.

2. A vortex separator for separating foreign matter from a flowing viscous liquid stream, said apparatus comprising an inlet conduit of uniform internal cross-sectional area, a casing having a smooth cylindrical internal side wall and end walls, said inlet conduit and casing being so arranged to cause the fluid to rotate about the axis of said cylindrical casing, an elongated separation tube having a diameter substantially less than the diameter of said casing and having one end connected to said end wall of the casing concentric with said axis, said separation tube having a threaded joint adjacent the other end, the upper portion of said separator tube being internally relieved at said joint to provide a dirt recess, the upper edge of the lower portion of said separator tube having an outwardly tapered end to provide an outwardly sloped dirt collecting surface at the base of the recess, a laterally directed outlet pipe to drain dirt from the recess, a relatively small air outlet pipe in the center of said lower portion of said separator tube having the inlet centrally located just below the threaded joint said separator tube discharging the liquid free of dirt and air below said air outlet pipe.
